PAPER-CUTTING MACHINE

Frederick D. McLaughlin, Shaker Heights, Ohio,
assignor to The Chandler & Price Company,
Cleveland, Ohio, a corporation of Ohio

Application November 5, 1943, Serial No. 509,055

8 Claims. (Cl. 164—53)

The present improvements, relating as indicated to paper cutting machines, have more particular regard to means for operating the cutter bar in such machines.

In paper cutters such as are employed in print shops and book binding establishments, as is well known, a stack of sheets supported against a gauge on a suitable table is clamped in place and a knife is forced downwardly through the stack in order to cut the same to desired dimensions. In heavier machines it is usual to employ power to operate the bar which carries such knife or cutter and also in some cases the clamp. While I am aware that in Patent No. 1,880,598 to R. S. Tyler et al., dated October 4, 1932, hydraulic power means are disclosed for operating the latter, so far as I know similar means have never been successfully applied to the operation of the knife or cutting mechanism proper.

One object accordingly of the present invention is to provide hydraulic means suitable for operating the knife or cutter bar in a paper cutting machine of the type in question. A further object is to provide such a mechanism which will pull or force the knife through the paper to be cut and then return the knife to the top of its stroke ready for fresh operation. Another object is to provide a control for such hydraulic means which will render it necessary for the operator to utilize both hands when the knife is thus being pulled or moved to cut the paper.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a front elevation of a paper cutting machine wherein my improved hydraulic operating means have been incorporated;

Fig. 2 is an end elevation of such machine as viewed from the right in Fig. 1;

Fig. 3 is a lay-out more or less schematic in character of the hydraulic operating means; and

Fig. 4 is a sectional detail of the connection between the hydraulic piston and knife bar of the machine.

Referring to the general construction of the machine as illustrated in Figs. 1 and 2, such machine will be seen to comprise a suitable base 1

5 on which is supported the table 2 designed to receive the stack or pile of sheets to be cut. For the purpose in hand it has been deemed unnecessary to illustrate either the adjustable gauge whereby such stack would be located on said table or the clamp whereby the stack after being thus located is firmly held in place during the cutting operation.

Rising above bed 1 at each end thereof are 10 slotted side frames 3 which are connected above by a cross member 4. The slots in such side frame reciprocably receive the bar or frame 5 to the lower edge of which the knife 6 is attached. Such knife bar is supported by means of parallel 15 links 7 from cross frame member 4 so that upon being lowered from the position shown in Fig. 1 said bar, together with the knife 6 carried thereby, will at the same time be moved longitudinally so as to impart desired sliding cutting movement to the knife. One end 5a of knife bar 5 is extended so as to project beyond the adjacent slotted side frame 3 and it is to this end that the hydraulic operating means now to be described are connected.

20 The principal element of such hydraulic operating means is a cylinder 10 fixedly secured to the front face of main frame 3 at an angle such that its axis will be approximately aligned with the outer end of projection 5a on the knife bar.

25 A piston 11 reciprocably mounted in said cylinder carries a piston rod 12 which projects through the upper end of the cylinder and is connected by means of a link 13 with said cutter bar projection 5a. This link, as best shown in Fig. 4, comprises two rod-like parts, the adjacent ends of which are oppositely threaded and are engaged by a correspondingly threaded nut 14 so that by rotation of the latter said link may be lengthened or shortened within limits as desired. By the 30 means just described it will be seen that the position of the knife at the end of its cutting stroke can be changed without altering the stroke of the piston.

35 A pump 20 is provided to supply oil or other liquid through suitable connections to the respective ends of cylinder 10 whereby reciprocation of piston 11 is effected. Such pump 20 is preferably of the circulating type having a variable displacement at constant speed so as to deliver a practically pulsationless current of oil to the cylinder. Such oil is taken from a tank 21 and discharged through a main line 22 in which is interposed a valve 23 for relieving excessive pressure through a connection 24 to the return line 25.

The flow of liquid supplied by the pump through line 22 and the return of such liquid through line 25 is subject to the control of two valves 26 and 27 respectively equipped with operating levers 28 and 29 which project forwardly from the machine below table 2 within convenient reach of the operator as he stands in front of the machine. As will be presently explained, it is necessary for the operator to grasp both these levers by his respective hands and thus actuate the corresponding valves in order to effect downward movement of the knife bar, and if either hand be removed from the control lever movement of the bar will automatically stop. In this way it is rendered certain that the operator's hands will be at all times out of danger from the descending knife.

Associated with control valves 26 and 27, a third valve 30 is provided adjacent the upper end of the cylinder 10, this valve constituting an automatic kick-out which prevents further movement of the piston in the cylinder and thus of the knife bar at the upper end of the stroke of said piston, i. e. when said knife bar has been raised to its uppermost position. This valve is designed to be operated by means of a cam-shaped dog 31 adjustably mounted on an arm 32 attached in parallel relation to piston rod 12. By shifting the position of the dog on said rod the point in the movement of the piston at which the supply of fluid producing the upward stroke is thus automatically cut off by valve 30 may be varied. In other words, depending upon the height of the stack of paper to be cut, the knife bar may be brought to a stop at any desired elevation above the table 2 and there held ready for a repeat operation by again actuating simultaneously the two control valves 26 and 27.

The particular construction of valves 26, 27 and 30 forms no part of the present invention, but typical valves suitable for the purpose are diagrammatically illustrated in Fig. 3 along with the connections therebetween and with the cylinder 10 and the main supply and return lines 22 and 25. As thus illustrated, the valves are of multiport type with a plurality of pistons on a common stem so that by shifting such stems the aforesaid lines or branches thereof may be variously connected. Thus in the position of parts shown in Fig. 3 which represents the idle position of the machine, i. e. that in which the knife bar 5 is in raised position, the following connections obtain, viz.: There is an open path of flow for the liquid supplied to line 22 through branch 35, connected ports in valve 26, branch 36, connected ports in valve 27 to branch 37 of the return line. At the same time the connection between valve 27 and the lower end of piston 10 by way of branch 38 is closed so that the pressure of the liquid supplied through branch 39 to the upper end of the cylinder is ineffective to move the piston in said cylinder downwardly. The port in valve 27 wherewith branch 38 is connected was closed when the piston reached its indicated position due to actuation of valve 30 which served to place in communication through said valve, branch 40 leading from branch 36, and branch 41, which leads to the lower end of said valve 27, with the result that the piston-carrying stem of said valve is moved upwardly.

An inspection of the lay-out of Fig. 3 will show that downward movement of the stem of either valve 26 or valve 27 alone, and corresponding displacement of the pistons carried by said stems will be ineffective to change the pressure

conditions in cylinder 10. However, upon pressing both of said valve stems downwardly the following connections will be established between the main supply line 22 and return line 25, viz.:

- 6 Branch 39 to the upper end of cylinder 10 remains open but branch 38 from the lower end of said cylinder is connected through the ports of valve 27 to branch 36 and through ports in valve 26 to branch 42 which leads to return line 25. Accordingly, the pressure on the under side of the piston in cylinder 10 is relieved and the piston will move downwardly imparting to the knife a corresponding downward or cutting stroke. Upon the completion of such stroke the operator, by releasing pressure on the stems of both valves 26 and 27, will permit the latter to return to the idle position first described above. Incidentally to the downward movement of the piston in cylinder 10, valve 30 being relieved from engagement with dog 31 returns to its normal position in which branch 41 is connected through the ports in said valve with branch 43 and thence to the return line 25. In this condition the valve is again ready upon reengagement of the dog with its stem to cut off the upward movement of the piston and cylinder 10 when the latter is again operated.

From the foregoing description it will be seen that with the pump running so as to supply oil or equivalent liquid under substantially constant pressure to line 25, the piston in cylinder 10 will normally actuate the knife bar to raise the same, and in order to cause reverse movement of the piston to lower the knife bar it is necessary for 30 the operator to depress the stems of both of the valves 26 and 27. At any time during such down stroke of the piston and blade such stroke may be reversed by releasing the control valves. Moreover, the adjustable dog associated with the rod 32 of piston 11 in cylinder 10 whenever it engages the stem of valve 30 will stop further upward movement of said piston, leaving the same ready for actuation downwardly whenever the operator is ready to repeat the cutting operation. The 40 use of dual control valves it will be seen makes it absolutely necessary for the operator to have both hands on the levers which operate said valves and these being located at some distance from the cutting knife it is impossible for either hand to be caught by the latter as it descends, for the moment either hand is removed from the corresponding control lever, operation of the piston 50 11 is automatically stopped.

It will be noted that the parallel links 7 whereby knife bar 5 is supported from cross frame member 4 are inclined at an angle to the latter, or in other words to the horizontal, and that the angle at which the cylinder 10, and thus the piston which operates in said cylinder is secured to the main frame, is opposite to that of said links. The effectiveness of the action of the piston on its down stroke is thus increased, the lateral shifting movement of the knife bar being taken care of by the link connection between the piston and the projecting end of said bar. At the same time by making such link adjustable the extent of the downward stroke of the knife can be very nicely gauged.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a paper cutting machine, the combination of a reciprocable knife, hydraulic means for reciprocating said knife, dual controls for said means, said controls requiring simultaneous actuation to be effective, and an adjustable stop limiting operation of said means in one direction.

2. In a paper cutting machine, the combination of a reciprocable knife, hydraulic means for reciprocating said knife, dual controls for said means, said controls requiring simultaneous actuation to be effective, and an adjustable stop adapted to render said controls ineffective.

3. In a paper cutting machine, the combination of a table, a knife reciprocable towards and from said table, a cylinder and piston adapted to reciprocate said knife, connections for supplying fluid under pressure to opposite ends of said cylinder, and dual valves controlling said connections, said valves requiring to be simultaneously actuated to effect movement of said knife towards said table.

4. In a paper cutting machine, the combination of a table, a knife reciprocable towards and from said table, a cylinder and piston adapted to reciprocate said knife, connections for supplying fluid under pressure to opposite ends of said cylinder, dual valves controlling said connections, said valves requiring to be simultaneously actuated to effect movement of said knife towards said table, and an adjustable stop movable conjointly with said piston adapted to render said controls ineffective.

5. In a paper cutting machine, the combination of a table, a knife reciprocable towards and from said table, a cylinder and piston adapted to reciprocate said knife, connections for supply-

ing fluid under pressure to opposite ends of said cylinder, said cylinder being mounted in fixed relation to said table and said piston having link connection with said knife, and an adjustable stop movable conjointly with said piston adapted to cut off such fluid supply upon predetermined upward movement of said knife.

6. In a paper cutting machine, the combination of a table, a knife reciprocable towards and from said table, angularly disposed parallel links supporting said knife, a cylinder and piston adapted to reciprocate said knife, said piston being mounted in fixed relation to said table at an angle opposite to the angle of said links, and another link connecting said piston with one end of said blade.

7. In a paper cutting machine, the combination of a table, a knife reciprocable towards and from said table, a cylinder and piston adapted to reciprocate said knife, connections for supplying fluid under pressure to opposite ends of said cylinder, dual valves controlling said connections, said valves requiring to be simultaneously actuated to effect movement of said knife towards said table, and levers for actuating said valves disposed below said table.

8. In a paper cutting machine the combination of a table, a knife reciprocable towards and from said table, angularly disposed parallel links supporting said knife, a cylinder and piston adapted to reciprocate said knife, said piston being mounted in fixed relation to said table at an angle opposite to the angle of said links, and another link connecting said piston with one end of said blade, said last-named link being adjustable in length.

FREDERICK D. McLAUGHLIN.
